UNITED STATES PATENT OFFICE.

OTIS A. MYGATT, OF NEW YORK, N. Y.

COMPOUND REFLECTOR FOR ARTIFICIAL LIGHTS.

No. 821,810.

Specification of Letters Patent.

Patented May 28, 1906.

Application filed July 13, 1905. Serial No. 262,549.

To all whom it may concern:

Be it known that I, OTIS A. MYGATT, a citizen of the United States, residing at New York, in the county of New York and State 5 of New York, have invented certain new and useful Improvements in Compound Reflectors for Artificial Lights, of which the following is a specification, reference being had therein to the accompanying drawings.

This invention relates to shades and reflectors for artificial lights.

The object of the invention is to so combine with a reflector or shade-reflector composed of prismatic glass an auxiliary or coöperating cover therefor as to increase the efficiency of such reflector.

The invention may be used as a combined shade and reflector with electric incandescent lamps and other light sources; and it consists, essentially, of a combination of different reflecting-surfaces and produces results unattainable by any other means within my knowledge.

It is a well-known fact that reflectors made 25 of transparent glass having the outer surfaces formed in prismatic ribbings of substantially ninety-degree angles are highly efficient as reflectors and not subject to deterioration, as is the case with reflectors having polished 30 metallic surfaces. As prisms of ninety degrees receive the incident rays at angles of substantially forty-five degrees, which angle is less than the angle at which total reflection takes place, it follows that a portion of 35 the light is transmitted by such reflectors. In some cases this is advantageous, as it furnishes illumination in the regions above the level of the reflector; but in other cases it is 40 decidedly objectionable—as, for example, when a reflector is in such position that the transmitted light would shine directly into the eyes. In such cases it is desirable that a 45 "shade"—that is, an opaque substance—should be used to intercept the upward rays of light. Such shades are commonly constructed of some opaque substance having a white inner surface, which acts as a diffuse-reflect. Such diffuse-reflectors, however, are less efficient than prismatic glass, and especially are incapable of concentrating the 50 light in any particular direction. My improved reflector-shade secures the advantages of both the prism-glass reflector and the opaque shade with white reflecting-surfaces.

In practice I prefer to use a prism-reflector of conical shape, since this is the shape to which

the superimposed shade or covering can be most readily attached; but I do not limit myself to any particular form or contour of reflector.

Figure 1 is a side elevation of a common prismatic-glass reflector. Fig. 2 is a perspective view of a smooth frustum of a hollow cone—say of pasteboard—adapted to neatly cover the body of the reflector, Fig. 1. Fig. 3 is an enlarged cross-section of glass reflector and cover—say about at line 3, Fig. 1. Fig. 4 is a diagram showing lines of reflection of a light-ray by the prisms of the reflector. Figs. 5 and 6 are diagrams showing curves of reflection by the reflectors singly and combined.

The cover 2 is preferably applied to reflector 1, so as to rest only on the apexes of the prisms. As will be seen, the cover 2 substantially corresponds in its frusto-conical shape with the body 1 of the reflector. The same general fact is true of other forms.

Fig. 4 shows the line of reflection of a light-ray, *a b c d*, by one of the prisms of reflector 1, as well understood in this art.

Fig. 3 shows a horizontal section of my combined shade and reflector, in which 1 is the prism-glass reflector, and 2 the shade or cover. This shade or cover may be made of plain white paper or cardboard, or the cardboard may be white inside and of any desired color outside. Opal glass, white sheet-celluloid, sheet-aluminium, or any other suitable material may be used. The material chosen is formed into a shape similar to the shape of the prism-glass reflector, and the shade thus formed is placed so as to rest upon and be supported by the reflector. The light transmitted by the prism-glass thus falls upon the white or light-colored inner surface of the cover 2 and is reflected backwardly through the transparent glass of the reflector. The increase in reflected light thus produced is clearly shown in the curves of intensity, Fig. 5, the curve A showing light from reflector 1 and B from the combination. The advantage of the combination, particularly where it is desired to reflect as much as possible of the light directly below the reflector, is shown in the curves, Fig. 6, in which A' shows the distribution obtained by the transparent-glass reflector alone and B' the distribution obtained by the shade of white inner surface alone. The use of the white inner surface in connection with a glass shade also improves the resulting illumina-

tion by preventing streaks, spots, or unevenly-illuminated surfaces. I am aware that an attempt to accomplish this purpose has been made by painting or enameling the outer surface of the prisms of a prismatic reflector; but I have found it impossible to secure in this manner results having any advantages whatever over the white surface or diffusing-reflector alone. That this must be the case will appear when it is considered that the reflecting power of prisms is destroyed as such when their surfaces are brought into optical or molecular contact with other substances. The result is that a prism-glass reflector with the prisms painted or enameled with a white substance is less efficient than a similar-shape white, opaque, or cardboard reflector. My cover 2 does not touch the plane or reflecting faces of the reflecting-prisms.

What I claim is—

1. The combination with a glass reflector having prisms on its outer surface, of a separate light-reflecting body, with whitish interior surface said inner surface being smooth and lying in a curve close to the apexes of the prisms and above the depressions between the prisms. 25

2. The combination with a frustum-shaped glass reflector having reflecting-prisms on its outer surface, of a similar-shaped opaque reflector of uniform thickness lying in a curve close to the apexes of the prisms. 30

In testimony whereof I affix my signature in presence of two witnesses.

OTIS A. MYGATT.
